UNITED STATES PATENT OFFICE.

ALEXANDER J. NICHT, JR., OF MILWAUKEE, WISCONSIN, ASSIGNOR TO ALLIS-CHALMERS MANUFACTURING COMPANY, OF MILWAUKEE, WISCONSIN, A CORPORATION OF DELAWARE

MOTOR-CONTROL APPARATUS.

1,399,983.

Specification of Letters Patent. Patented Dec. 13, 1921.

Application filed August 23, 1919, Serial No. 320,287. Renewed July 1, 1921. Serial No. 481,932.

To all whom it may concern:

Be it known that ALEXANDER J. NICHT, Jr., a citizen of the United States, residing at Milwaukee, in the county of Milwaukee and 5 State of Wisconsin, has invented a certain new and useful Improvement in Motor-Control Apparatus, of which the following is a specification.

This invention relates to motor-control apparatus and is particularly useful in connection with the control of a plurality of motors used for operating diverse types of mills such as sugar, metal, paper, etc. It frequently occurs in various types of mills 10 where each of a plurality of sets of rolls, for example, is driven by an individual motor, that it becomes desirable to change the relative speeds at which the sets of rolls are operated. After the relative speeds have 15 been determined and given the proper proportions it may then become desirable to increase or decrease the speed of the mill as a whole, that is, the speed of each individual set of rolls or whatever elements the mill 20 may consist of is to be raised or lowered while keeping the relative speeds proportionately substantially the same.

One of the objects of this invention is the provision of an apparatus whereby motors 30 may be so controlled as to give the desired results stated above. Another object of this invention is the provision of a rheostat of the liquid type for accomplishing the above mentioned results. Other objects will appear 35 hereinafter as the description of the invention proceeds.

The novel features of this invention will appear from this specification and the accompanying drawings disclosing one embodiment of said invention, and all these novel features are intended to be pointed out in 40 the claims.

In the drawings Figure 1 is an end elevation of a rheostat embodying the features of 45 the invention, a portion of the casing being broken away.

Fig. 2 is an elevation of that side of the rheostat upon which simultaneously controlled weirs are located as will more fully 50 be pointed out hereinafter, a portion of the casing being broken away.

Fig. 3 is an elevation of that side of the rheostat opposite to that of Fig. 2, a portion 55 of the casing and other parts being broken

away in order to more clearly show the 55 mechanism.

In the form shown, the rheostat comprises a composite tank 1 made up of any number of individual receptacles 2, 3, 4, dependent upon the number of motors to be controlled. 60 As far as the operation of the apparatus is concerned it is not material whether the receptacles 2, 3, 4 form compartments of a main tank or are themselves individually built tanks. Each receptacle 2, 3, 4 contains suitable electrodes 5 for connection to circuits of the motors to be controlled, which electrodes may be supported in said receptacles in any desired manner.

Referring now more particularly to Fig. 2 70 it will be seen that each receptacle is provided at the side shown, with one weir (6, 7 or 8). Referring to Fig. 3, the receptacles are provided at the other side with the weirs 9, 10 or 11. The weirs are here shown as of 75 the shutter type comprising a plurality of shutters 12, the operation of which is obvious from a mere inspection of the figures, and in particular Fig. 1. The operation and advantages of weirs of this type have been 80 fully set forth in the patent thereon granted to Allis-Chalmers Manufacturing Company, assignee of H. C. Holthoff, inventor, 1,309,802, July 15, 1919. The use of weirs of other types is, however, within the contemplation of the present invention.

The weirs 6, 7, 8 are operated by operating rods 13^a, 13^b, 13^c respectively, by means of a common shaft 14 acting through cranks 15^a, 15^b, 15^c. The shaft 14 may be oscillated to 90 the desired extent by the mutilated bevel gears 16, 17, the gear 16 moving with the lever 18 oscillatable by any suitable means such as the screw shaft 19 which may be rotated by means here shown as a hand wheel 95 20. The extent of the motion of the screw shaft 19 may be indicated by any suitable indicator 21 which will thus indicate the extent of opening or closure of the weir shutters. The parts of the weirs are counterbalanced by means of the weight 22 connected to the shaft 14.

The weirs 9, 10, 11 while operated by rods 13^a, 13^b, 13^c in a manner similar to the weirs 6, 7, 8 are not necessarily operated in unison, 105 but may be operated dissimultaneously by reason of the fact that each weir is provided with an individual operating shaft as 24^a,

- 24^b, 24^c connected through cranks 23^a, 23^b, 23^c to the respective operating rods. Each weir is provided with an individual actuating motor 25^a, 25^b, 25^c. These motors are adapted to actuate their respective weirs through the operating rods thereof by any suitable means such as the gear driven traveling nut operating upon the slotted lever 26, shown in Fig. 1. Each actuating shaft 10 is provided with an individual counter-weight 27^a, 27^b, 27^c.
- In order that the electrode-containing receptacles may be supplied with liquid resistance material each is provided with an inlet opening 28^a, 28^b, 28^c (see Fig. 2), which openings are connected to the manifold 29 in turn connected to the pump 30 driven by the motor 31. The liquid resistance material which flows through and over the various weirs drops into the common reservoir receptacle 32, where, if desired, it may be cooled by especially provided means, and then pumped into the manifold 29 by the pump 30.
- 25 In order to predetermine the rate of supplying liquid resistance material to the respective receptacles, baffles 33^a, 33^b, 33^c are provided, each operated by a rod 34 which may be raised and lowered in any suitable manner as by means of a nut 35 (see Fig. 1.) The rods 34 extend upwardly to a convenient point for adjustment. The baffles also serve the purpose of preventing surface agitation, as boiling and foaming, of the liquid as it enters the receptacles and immerses the electrodes.
- Control and limit switches 36 are provided for each motor 25^a, etc., which may be operated in any suitable manner as by a chain drive 37 connected to the shafts 24^a, etc. The motors 25^a, etc., may be controlled by any system of suitable and desirable type.
- The operation of the apparatus is as follows: It being assumed that the electrodes of the respective receptacles are connected to the motors to be controlled in a manner well known to those skilled in the art and it is desired to start said motors from standstill the weirs 6, 7, 8 are closed to any desired extent by means of the hand wheel 20. The pump motor 31 may then be started in any suitable manner whereupon liquid resistance material will be supplied to the receptacles 2, 3, 4 at predetermined rates. 50 The rate of immersion, and thus the rate of increase of speed of any given motor may then be further determined by the amount of closure of the respective weirs 9, 10, 11. The amount of closure of said weirs is of course controlled by the motors 25^a, 25^b, 25^c, and as these motors are individually controllable in any desired manner the rate of increase or decrease of speed of any of the controlled motors may also be controlled 55 in any desired manner. If it is desired, for example, that the motor connected to the electrode in receptacle 2 shall operate at a higher speed than the motor associated with the receptacle 3, the weir 9 will be closed to a greater extent than the weir 10. The same clearly applies to the relative speeds as between any of the other motors.
- Assuming that the respective mill motors have been brought to aid are being maintained at the desired relative speeds and it is desired to change the speed of all of the motors in unison a proportionate amount with respect to their individual speeds, the hand wheel 20 is operated, say, to open the weirs 6, 7, 8, thereby lowering the respective levels in the receptacles 2, 3, 4, proportionate amounts. It is of course obvious that the speed of all of the motors may be correspondingly raised by again closing the weirs in question.
- It may be noted that the receptacles may be of different sizes as can be seen, for example, in Fig. 2 where the receptacle 2 is shorter than receptacles 3, 4, the corresponding weirs being then also of a different size. This provides for the control of motors of a different size necessitating the use of electrodes of different sizes. The difference in size of weirs 6, 7, 8 will thus maintain the desired proportion, as determined by weirs 9, 10, 11, in the liquid levels in the respective receptacles as the weirs 6, 7, 8 are opened and closed to a greater or less extent.
- It should be understood that it is not desired that the invention claimed be limited to the exact details of construction shown and described, for obvious modifications will occur to a person skilled in the art.
- It is claimed and desired to secure by Letters Patent:
1. A motor-control apparatus comprising a plurality of rheostats, means whereby the resistance offered by said rheostats may be brought to and maintained at predetermined like values or different values, and means operable independently of said first mentioned means whereby the resistances may be simultaneously varied keeping the relative proportions substantially the same.
  2. A rheostat comprising a plurality of electrode-containing receptacles, means for supplying liquid resistance material to each of said receptacles, means whereby the liquid levels in said receptacles may be brought to and maintained at predetermined desired relative proportions, and means operable independently of said first mentioned means whereby the liquid levels may be simultaneously varied keeping said relative proportions substantially the same.
  3. A rheostat comprising a plurality of electrode-containing receptacles, means for supplying liquid resistance material to each of said receptacles at a predetermined rate, means for discharging liquid material from

- each of said receptacles at definite desired rates respectively whereby the liquid level is maintainable in each receptacle at a definite desired level, and means operable independently of said first mentioned means for discharging liquid material from each of said receptacles at a rate such that the relative levels will remain substantially the same.
10. 4. A motor-control apparatus comprising a plurality of rheostats, means whereby the resistance offered by said rheostats may be brought to and maintained at predetermined desired relative proportions, and means whereby the resistances may be simultaneously varied keeping said relative proportions substantially the same without disturbing the setting of said former means.
15. 5. A rheostat comprising a plurality of electrode-containing receptacles, means for supplying liquid resistance material to each of said receptacles, means whereby the liquid levels in said receptacles may be brought to and maintained at predetermined desired relative proportions, and means whereby the liquid levels may be simultaneously varied, keeping said relative proportions substantially the same without disturbing the setting of said former means.
20. 6. A rheostat comprising a plurality of electrode-containing receptacles, means for supplying liquid resistance material to each of said receptacles at a predetermined rate, means whereby said liquid material may be permitted to flow from said receptacles at respectively the same variable rate and other means whereby said liquid material may be permitted to flow from said receptacles at respectively different variable rates.
25. 7. A rheostat comprising a plurality of electrode-containing receptacles, means for supplying liquid resistance material to each of said receptacles at a predetermined rate, means whereby the liquid levels in said receptacles may be varied dissimultaneously and kept at definite like or different levels, and means whereby the liquid levels in said receptacles may be varied simultaneously.
30. 8. A rheostat comprising a plurality of electrode-containing receptacles, means for supplying liquid resistance material to said receptacles, a set of two weirs associated with each of said receptacles, manually operable means associated with one weir of each set for operating the associated weirs in unison, a plurality of electro-responsive means, one means associated with one weir of each set whereby said electro-responsive operated weirs may be operated dissimultaneously or simultaneously as desired.
35. 9. A rheostat comprising a plurality of electrode-containing receptacles, means for supplying liquid resistance material, means for connecting said supply-means to each of said receptacles, a set of two weirs associated with each of said receptacles, manually operable means associated with one weir of each set for operating the associated weirs in unison, and means whereby the liquid level in each of said receptacles, manually operated means associated with one weir of each set for operating the associated weirs in unison, a plurality of motors, one associated with one weir of each set whereby said motor operated weirs may be operated dissimultaneously or simultaneously as desired.
40. 10. A rheostat comprising an electrode-containing receptacle, means for supplying liquid resistance material to said receptacle, and two weirs for varying and maintaining the liquid level in said receptacle at desired points.
45. 11. A rheostat comprising a plurality of electrode-containing receptacles, means for supplying liquid resistance material to said receptacles, means associated with each receptacle for predetermining the rate at which liquid is supplied thereto comprising a baffle in the receptacles.
50. 12. A rheostat comprising a plurality of electrode-containing receptacles each having an inlet opening, means for supplying liquid resistance material connected to said inlet opening, and an adjustable baffle in the receptacle near each inlet opening.
55. 13. A rheostat comprising an electrode-containing receptacle, means for supplying liquid resistance material to said receptacle, and means associated with said receptacle for predetermining the rate at which liquid is supplied thereto and for minimizing agitation of the surface of the liquid in the receptacle.
60. 14. A rheostat comprising an electrode-containing receptacle having an inlet opening in the bottom thereof, a baffle near said opening, a rod connected to said baffle and extending upwardly therefrom to a point near the top of the receptacle, and means for giving vertical motion to said rod.
65. 15. A rheostat comprising an electrode-containing receptacle having an inlet opening in the bottom thereof and a substantially horizontal baffle near said opening.
70. 16. A rheostat comprising a plurality of electrode-containing receptacles, means for supplying liquid resistance material to said receptacles, a set of two weirs associated with each of said receptacles, means associated with one weir of each set for operating the associated weirs in unison, and a plurality of means, one means associated with one weir of each set whereby said last named weirs may be operated dissimultaneously or simultaneously as desired.
75. 17. A rheostat comprising a plurality of electrode-containing receptacles, means for supplying liquid resistance material to said receptacles, a set of two weirs associated with each of said receptacles, means associated with one weir of each set for operating the associated weirs in unison, and means whereby the remaining weirs may be operated dissimultaneously or simultaneously as desired.

4
operated dissimultaneously or simultaneously as desired.

18. A rheostat comprising a plurality of electrode-containing receptacles, said receptacles being adapted for connection to a plurality of motors respectively, means for supplying liquid resistance material to each of said receptacles at a predetermined rate, means whereby the liquid in said receptacles 10 may be varied dissimultaneously and kept at definite like or different operating levels, and means whereby the liquid levels in said receptacles may be varied simultaneously. 15 19. In combination, a plurality of motors for driving a machine operating on a substantially continuous web, a plurality of rheostats for controlling said motors respectively, means for independently varying the resistances offered by said rheostats where- 20 by the relative speeds of said motors may

be changed, and means for simultaneously varying the resistances in such manner that the speed of all of the motors may be varied while keeping their relative speeds constant.

25

20. In combination, a plurality of motors for driving a machine operating on a substantially continuous web, a plurality of liquid rheostats for controlling said motors respectively, means for independently varying the liquid levels in said rheostats whereby the relative speeds of said motors may be changed, and means for simultaneously varying the liquid levels of said rheostats in such manner that the speed of all the 30 35 motors may be varied while keeping their relative speeds constant.

In testimony whereof, the signature of the inventor is affixed hereto.

ALEX. J. NICHT, JR.
